UNITED STATES PATENT OFFICE.

JOHN J. SELTENREICH, OF CHICAGO, ILLINOIS. ASSIGNOR OF ONE-HALF TO EDWARD F. BRALEN, OF CHICAGO, ILLINOIS.

COLLAR-IRONING MACHINE.

1,120,416.

Specification of Letters Patent.

Patented Dec. 8, 1914.

Application filed September 2, 1913. Serial No. 787,580.

To all whom it may concern:

Be it known that I, JOHN J. SELTENREICH, a resident of Chicago, in the county of Cook and State of Illinois, have invented 5 certain new and useful Improvements in Collar-Ironing Machines, of which the following is a full, clear, and exact description.

The invention relates to machines for ironing the edges of collars.

10 The present invention designs to provide an improved machine which comprises two ironing members between which the turned edge of the collar will be held, one of said members being heated, and a device for 15 squeezing the two members together to iron the edge of the collar.

A further object of the invention is to provide an ironing machine of improved construction.

20 The invention consists in the several novel features hereinafter set forth and more particularly defined by claims at the conclusion hereof.

In the drawings: Figure 1 is a rear elevation of a machine embodying the invention. Fig. 2 is a plan. Fig. 3 is a perspective of the movable, resilient ironing member. Fig. 4 is a central vertical section of the upper portion of the machine. Fig. 5 is a similar 30 section of the lower portion of the machine. Fig. 6 is a section taken on line 6—6 of Fig. 5. Fig. 7 is a detail of one of the adjustable device carrying arms.

The machine comprises a hollow base 10 adapted to rest upon the floor and having a hollow standard 11 to the upper end of which is connected, by a screw-thread 12, a bifurcated supporting bracket 13. A head 14 is secured to the upper end of bracket 13 by bolts 15 and the outer portion of this head is provided with an annular chamber 16 which is formed between a wall 17 and the head 14. This chamber serves as a heater to which steam is admitted through an inlet 18 and exhausted therefrom through an outlet 19. The upper portion of wall 17 is provided with a flared groove 20 which is adapted to receive the turned edge of a collar. The chamber 16 and its surrounding walls constitute a heated ironing ring having a groove therein for ironing one side of the turned edge of a collar. In the present invention this ring is stationary.

The other ironing member, which is

adapted to pass into the collar to squeeze 55 and iron the turned edge in conjunction with the grooved ring, consists of a strip of metal 22, which is slotted as at 23 and slotted as at 24, so that it will be flexible, inwardly and outwardly, to iron and work 60 the edge of the collar in the grooved ring when pressure is applied to one of the members to squeeze the two members together. The top of strip 22 is expanded, as at 25, and provided with a wear-strip 26. The 65 ends of strip 22 are extended to form ears 27 which are pivotally held by a rod 28 mounted in brackets 29 secured to the ring 17. Strip 22 is formed with apertures 30 which fit loosely around rod 28 so that the 70 different portions of the strip 22 may be squeezed into the groove 20 of ring 17 to effectively work and iron the turned edge of a collar in the groove. A handle 31 is secured to member 22 whereby the latter may 75 be swung into and out of operative relation with the ironing member 17 to permit a collar to be inserted between the ironing members and removed from the grooved member. A stop 32 limits the backward 80 swing of strip 22.

A plurality of presser devices are provided which are rotated over member 22 to successively squeeze the different portions thereof downwardly against the inside 85 of the edge of the collar in groove 20 of member 17. Each presser device consists of a roller 36 journaled on the end of an angular shaft 37 which has one end secured in a split collar 38 on the end of a shaft 39 90 which is slidably held in slots 40 formed in a rotatable bracket or head 41. When this head is rotated with the rollers 36 in engagement with the wear-strip 26 of member 22, they will squeeze the different portions of members 22 against the turned edge 95 of the collar and, in conjunction with the heated grooved member 17, will effectively iron the edge of the collar without tearing it. These presser devices are alternately rotated in opposite directions or oscillated.

The mechanism for rotating the head 41 which carries the presser devices, comprises a shaft 43 which is mounted in lugs 44 at the rear of bracket 13, an arm 45 rigid on 105 said shaft, a link 46 pivoted to said arm and to an arm 47 on a shaft 48 to which is secured a beveled gear 49 meshing with a

beveled pinion 50 which is secured to the lower end of a sleeve 51 which is journaled in a bearing 52 which is secured to head 41 and this sleeve is secured at its upper end to the head 41. When the rollers 36 are in operative relation to the ironing member 22 and power is applied to shaft 43 by means of a pulley 43' thereon, arm 45 will be rotated to operate link 46 which will operate arm 47 to rotate gear 49 back and forth. Such operation of gear 49 will operate pinion 50 to rotate the head 41 back and forth over the ironing member 22. Such operation will cause the presser-devices to successively squeeze the ironing members together with the edge of the collar therebetween.

Mechanism is provided for raising the presser devices to permit member 22 to be swung upwardly and to force the devices downwardly onto said member during the ironing operation. This mechanism comprises a rod 60 which is slidably held in sleeve 51 and is pivoted to the end of an arm 61 which is rigidly secured to shaft 39 to which the presser-devices are secured. Angular shafts 37 are eccentrically disposed or offset with respect to the axis of shaft 39 so that rotation of said shaft will swing the rollers 36 upwardly. Clamping collars 38 are adjustably secured to shaft 39 by means of bolts 38' whereby the split collars may be clamped to the shaft in position to cause them to exert the desired pressure upon ironing member 22. When rod 60 is lowered from the position shown in full lines, Fig. 4, to that indicated in dotted lines, arm 61 will be operated to move shaft 39 and the presser-devices bodily toward the axis 40 of the rotating head 41 and will also cause the shaft to be turned to raise the devices away from member 22. Upward movement of rod 60 will restore the devices into operative relation with the member 22. The lower end of rod 60 is swiveled in a guide 65 which is slidable in the hollow column 11 and is connected thereto so as to be raised and lowered thereby by means of a pin 66 extending through a groove adjacent the lower end of said rod. This connection permits rod 60 to rotate with head 41 without rotating the mechanism for shifting said rod. The latter comprises a link 67 which is pivoted to guide 65, as at 68, and 55 to an arm 69 which is secured to a treadle-shaft 70. The latter is journaled in the base 10 and is provided with a treadle-lever 71 having oppositely disposed foot pieces whereby the shaft may be operated in either direction. When the shaft is operated in one direction to render the presser devices operative, the arm 69 and link 67 will pass into dead center relation, will raise rod 60 to operate arm 61 and the devices and will lock them in operative relation.

tion to member 22. Operation of treadle 71 in the opposite direction will cause arm 69 to release the device operating connection and to lower rod 60 to move the devices inwardly and upwardly to clear the ironing member 22 and permit the latter to be swung upwardly.

The invention thus exemplifies an improved machine in which there is a stationary heated, grooved ring, a co-operating ironing member adapted to pass into the collar and into the groove, and presser-devices for working over the latter member to cause the edge of the collar to be ironed between said members.

The invention is not to be understood as restricted to the details set forth, since these may be modified within the scope of the appended claims without departing from the spirit and scope of the invention.

Having thus described my invention, what I claim as new, and desire to secure by Letters Patent, is:—

1. In a collar ironing machine, the combination of two ironing rings, one of which is stationary and formed with a groove to receive the folded edge of a collar, the other ring being formed to engage the inside of said edge and being movable into and out of operative relation with the grooved ring, means for heating one of the rings, a device for pressing the rings together to iron the collar, movable relatively to the rings to apply pressure to different portions thereof and mechanism for shifting said device relatively to said rings.

2. In a collar ironing machine, the combination of two ironing rings, one of which is stationary and formed with a groove to receive the folded edge of a collar, the other ring being formed to engage the inside of said edge and being movable into and out of operative relation with the grooved ring, means for heating one of the rings, a device mounted to press the rings together to iron a collar between them and rotatable relatively to said rings to apply pressure to different portions thereof and mechanism for rotating said device relatively to said rings.

3. In a collar ironing machine, the combination of two ironing rings, one of which is stationary and formed with a groove to receive the folded edge of a collar, the other of which is pivotally sustained to swing into and from the grooved ring, means for heating the grooved ring, a device for applying pressure to the movable ring to iron the collar, movable relatively to the ring to apply pressure to different portions thereof, and mechanism for operating said device relatively to the movable ring.

4. In a collar ironing machine, the combination of two ironing rings, one of which is stationary and formed with a groove to receive the folded edge of a collar, the other

- of which is pivotally sustained to swing to and from the grooved ring, means for heating the grooved ring, a device for applying pressure to the movable ring to iron the 5 collar, mounted to rotate relatively to the movable ring to apply pressure to different portions thereof, and mechanism for rotating said device relatively to the movable ring.
- 10 5. In a collar ironing machine, the combination of a stationary ring having a groove to receive the folded edge of a collar, a ring formed to engage the inside of said edge and pivotally sustained so it may be 15 swung into and out of the groove, means for heating the stationary ring, a presser device for engaging the movable ring to iron the collar, said device being movable into and out of operative relation with the movable ring, mechanism for shifting said device into and out of operative position and mechanism for operating the device over the movable ring.
6. In a collar ironing machine, the combination of a stationary ring having a groove to receive the folded edge of a collar, a ring formed to engage the inside of said edge and pivotally sustained so it may be 25 swung into and out of the groove, means for heating the stationary ring, a rotatable presser-device for engaging the movable ring to iron the collar, said device being movable into and out of operative relation with the movable ring, mechanism for shifting the device into and out of operative position and mechanism for rotating said device over the movable ring.
7. In a collar ironing machine, the combination of a stationary ring having a groove therein for the turned edge of a 40 collar, a ring comprising a resilient strip formed to engage the inside of said edge and movable into and out of operative relation with the grooved ring, means for heating the stationary member, and a device engaging the movable ring to apply pressure thereto to iron the collar and movable relatively to said ring to apply pressure to different portions thereof.
- 45 8. In a collar ironing machine, the combination of a stationary ring having a groove therein for the turned edge of a collar, a ring comprising a resilient strip formed to engage the inside of said edge and movable into and out of operative relation with the grooved ring, means for heating the stationary member, a device for engaging the movable ring to iron the collar, movable relatively to the movable ring to 55 apply pressure thereto, and mechanism for shifting said device relatively to the movable ring.
- 60 9. In a collar ironing machine, the combination of a stationary ring having a groove therein for the turned edge of a 65 collar, a ring comprising a resilient strip formed to engage the inside of said edge and movable into and out of operative relation with the grooved ring, means for heating the stationary member, a movable ring 70 having an expanded upper edge, a presser-device for engaging said expanded edge, and means for operating said device over the movable ring.
10. In a collar ironing machine, the combination of two ironing members, one of which is provided with a groove for receiving the turned edge of a collar, the other being formed to engage the inside of said edge, means for heating the grooved member, one of said members being movable to and from the other to permit a collar to be placed between them and removed therefrom, a device for squeezing the members together to iron the collar, mechanism for 80 rotating said device, and mechanism for shifting said device pivotally and bodily to move it into and out of operative position with one of said members.
11. In a collar ironing machine, the combination of two ironing members, one of which is provided with a groove for receiving the turned edge of a collar, the other being formed to engage the inside of said edge, means for heating the grooved member, one of said members being movable to and from the other, to permit a collar to be placed between them and removed therefrom, a device for squeezing the members together to iron the collar, mechanism for 85 rotating said device including a rotatable head, a shaft pivotally and slidably movable in the head and to which said device is connected, and mechanism for moving the shaft bodily and pivotally.
12. In a collar ironing machine, the combination of two ironing members, one of which is provided with a groove for receiving the turned edge of a collar, the other being formed to engage the inside of said 90 edge, means for heating the grooved member, one of said members being movable to and from the other, to permit a collar to be placed between them and removed therefrom, a device for squeezing the members together to iron the collar, mechanism for 95 rotating said device including a rotatable head, a shaft slidably mounted in the head, a rod slidably mounted in the head and to which said device is secured, and a connection between said rod and said shaft.
13. In a collar ironing machine, the combination of two ironing members, one of which is provided with a groove for receiving the turned edge of a collar, the other being formed to engage the inside of said edge, means for heating the grooved member, one of said members being movable to and from the other to permit a collar to be placed between them and removed there- 100 105 110 115 120 125 130

from, a device for squeezing the members together to iron the collar, mechanism for rotating said device, including a rotatable head, a rod slidably mounted in the head, 5 a shaft slidably mounted in the head and to which said device is secured, and an arm secured to said shaft and pivoted to said rod.

14. In a collar ironing machine, the combination of two ironing members, one of which is provided with a groove for receiving the turned edge of a collar, the other being formed to engage the inside of said edge, means for heating the grooved member, one of said members being movable to and from the other, to permit a collar to be placed between them and removed therefrom, a device for squeezing the members together to iron the collar, mechanism for 15 rotating said device, including a rotatable head, a shaft movably mounted in the head, an adjustable connection between the shaft and said device, and mechanism for operating the shaft to move the device into and 20 out of operative position.

15. In a collar ironing machine, the combination of two ironing members, one of which is provided with a groove for receiving the turned edge of a collar, the other being formed to engage the inside of said edge, one of the members being movable to and from the other to permit a collar to be 25 placed between them, a plurality of presser-devices, a shaft to which said devices are secured, a rotatable head, mechanism for rotating the head, and mechanism for oper-

ating the shaft to move said devices into and out of operative relation with one of the members.

16. In a collar ironing machine, the combination of two ironing members, one of which is provided with a groove for receiving the turned edge of a collar, the other being formed to engage the inside of said edge, one of the members being movable to 40 and from the other to permit a collar to be placed between them, a plurality of presser-devices, a shaft, adjustable connections between each of said devices and said shaft, a rotatable head, mechanism for rotating 45 the head, and mechanism for operating the shaft to move said devices into and out of operative relation with one of the members.

17. In a collar ironing machine, the combination of two ironing members, one of which is provided with a groove for receiving the turned edge of a collar, the other being formed to engage the inside of said edge, one of the members being movable to and from the other to permit a collar to be 50 placed between them, a plurality of presser-devices, a shaft to which said devices are 55 secured, a rotatable head, mechanism for rotating the head, said shaft being slidable and rotatable in the head, and mechanism for moving the shaft bodily and rotating it to shift said devices into and out of operative position.

JOHN J. SELTENREICH.
